UNITED STATES PATENT OFFICE.

EUGENE N. PHILLIPS, OF SAN ANTONIO, TEXAS, AND HARVEY H. DICK, OF LINCOLN, ILLINOIS, ASSIGNEES TO AMERICAN STEAM BOILER CLEANER COMPANY, A CORPORATION OF TEXAS.

BOILER SKIMMER OR CLEANER.

1,315,574.

Specification of Letters Patent.

Patented Sept. 9, 1919.

Application filed May 9, 1917. Serial No. 167,549.

To all whom it may concern:

Be it known that we, EUGENE N. PHILLIPS and HARVEY H. DICK, citizens of the United States, residing at San Antonio and Lincoln, respectively, in the counties of Bexar and Logan, respectively, and States of Texas and Illinois, respectively, have invented certain new and useful Improvements in Boiler Skimmers or Cleaners, of which the following is a specification.

Our invention relates to new and useful improvements in boiler cleaners or skimmers, the primary object of our invention being the provision of a structure which may be built into or inclosed in steam boilers of various types and arranged to skim any scum, scale or other sediment, rising to the surface of water in the boiler because of use of impure water and to discharge it from the boiler so as to prevent permanent deposits of such matter upon the inner surface of the boiler and the outer surface of the fire tubes, and also prevent foaming and priming in the steam boiler.

More particularly, our invention is intended for use in the steam boilers of locomotives and one of the objects of our invention is the provision of an efficient supporting frame for the skimmer proper of such a character that it may be supported in all boilers of conventional type and firmly held in place, one of the preferred methods being to attach the supporting frame to the dry pipe of the boiler. The main supporting frame is tubular in construction and in fact forms a portion of the outlet system of the skimmer or cleaner and supports a second tubular structure which forms the inlet of the system and which includes certain skimmer pipes having slots or other openings through which the scum and scale may pass from the boiler.

A further object of our invention is the provision of novel means for maintaining the inlet frame at proper level to bring the slots or openings of the skimmer pipes at or approximately at the water level in the boiler.

In accomplishing this last mentioned object, certain tubular elements of the inlet portion of the system have oscillating joint connections with certain tubular elements or brackets of the outlet portion of the system so that the inlet portion of the system is swingingly supported in order that it may

adapt itself to changes in water level in the boiler during use. One important object of our present invention is, therefore, the provision of suitable oscillating joint structures for connecting the two portions of the system which will be of such a character as to withstand all strain and wear to which they are subjected in use and still afford a continuous uninterrupted passage for the mixture of water, steam and impurities passing from the boiler.

Various structures have been designed and tested for removing scum from the water in boilers of locomotives, but, in most instances, have been found inefficient as being too light and frail in construction, or as being so poorly supported within the boiler as to render it impossible for them to withstand the strong current in the high pressure water tubular boilers and the surging and hammering of water in the boilers produced by the sudden starting, stopping and rocking motion of the engine while running.

Another object which we have in view is, therefore, the construction of a skimmer or cleaner mechanism particularly designed for strength to withstand the strains to which it is normally subjected.

A further object of our invention is the provision of suitable valves and pipes for controlling the blowing off of scum, steam and water from the boiler, whereby a continuous but slight blowing off of such matter may be maintained at all times while the locomotive is running and whereby such matter may be rapidly blown off periodically at the will of the operator.

Furthermore, we seek to provide a boiler cleaner or skimmer possessing the above advantages which will be simple in construction, will be capable of being readily assembled, and which may be readily repaired as may be necessary, through injury or deterioration through wear.

With these and other objects in view, our invention will be more fully described, illustrated in the accompanying drawings, and then specifically pointed out in the claims which are attached to and form a part of this application.

In the drawings:

Figure 1 is an elevation of a conventional form of locomotive, showing a portion of the boiler in section and our improved boiler skimmer or cleaner in place;

Fig. 2 is a side elevation of the skimmer or cleaner;

Fig. 3 is a top plan view of the same;

Fig. 4 is a vertical sectional view taken 5 on the line 4-4 of Fig. 2, looking in the direction of the arrows;

Fig. 5 is a fragmentary longitudinal section taken on the line 5-5 of Fig. 2, showing one of the double oscillating joints employed, in detail, and also one of the floats 10 and its attaching bracket;

Fig. 6 is a sectional view taken on the line 6-6 of Fig. 5, looking in the direction of the arrows and showing the method of attaching one of the floats to one of the skimmer pipes;

Fig. 7 is a perspective view of one of the float attaching brackets;

Fig. 8 is a horizontal sectional view taken 20 on the line 8-8 of Fig. 4;

Fig. 9 is a fragmentary sectional view taken through the line 9-9 of Fig. 5;

Fig. 10 is a perspective view of the standard portion of one of the tubular brackets 25 employed;

Fig. 11 is an end elevation of a modified form of tubular bracket construction;

Fig. 12 is a sectional view taken on the line 12-12 of Fig. 11, looking in the direction of 30 the arrows;

Fig. 13 is a fragmentary perspective view of a still further modified form of supporting frame.

Corresponding and like parts are referred 35 to in the following description and indicated in all the views of the drawings by the same reference characters.

In order to insure a clear and accurate 40 understanding of our invention, its application and operation, we have illustrated it in connection with a conventional water tubular boiler 10 of a locomotive 11. As best shown in Fig. 1, our improved boiler cleaner or skimmer, indicated as a whole by the numeral 12, is supported within the boiler upon 45 the dry pipe 13 which, if possible, is the preferred construction.

Referring more particularly to Figs. 2, 3 and 4 of the drawings, it will be seen that 50 our improved boiler skimmer primarily includes a tubular supporting frame, indicated as a whole by the numeral 14, and a pair of tubular inlet frames, each indicated as a whole by the numeral 15. The tubular 55 supporting frame includes a pair of U-shaped brackets of the type best shown in Fig. 4. Each bracket has side or standard portions 16 which are tubular and which, at their lower ends, are closed by threaded plug caps 60 17 and which, at their upper ends, are internally threaded to receive elbow couplings 18. Pipe sections 19 and 20 are threaded into the alined ends of a T-coupling 21 and the former of these sections is threaded directly 65 into the elbow coupling of one of the

standards. The other of these pipe sections, in the present instance the section 20, is connected to a pipe section 22 threaded into the other elbow coupling by means of a union coupling 23 of any suitable type, this union 70 coupling being necessary to facilitate the assemblage of the parts or their ready disassembly in case of repairs. The two U-shaped brackets are identical in construction, as will be appreciated by reference to 75 Figs. 2 and 3 of the drawings, and form in effect the end members of the supporting frame, being connected by pipe sections 24, 25 and 26, the pipe sections 24 and 25, at one end, being threaded into the side branches of 80 the T-couplings 21. One of these pipe sections, as the section 24, is threaded into one of the alined branches of a T-coupling 27 and the other pipe section 25 is connected by 85 a union coupling 28 to the pipe section 26 which is threaded into the other of the alined branches of the T-coupling 27.

Each of the brackets is supported upon the dry steam pipe by a pair of yoke plates 29, the lower edges of which are cut-away or 90 otherwise shaped to conform somewhat to the curvature of the upper surface of the dry pipe and the ends of which are provided with vertically disposed sleeve sections 30 to engage against opposite sides of the 95 standard portions 16 of the brackets so that when bolts 31 are passed through the plates with the sleeve portions engaging the standards and are secured by nuts 32, the standard portions 16 of the brackets will be firmly 100 clamped between the yoke plates and held against movement. The inner faces of the yoke plates, at either side of their centers, are channeled or cut-away, as shown at 33, for the passage of the arms of a U-bolt 34 105 which encircles the lower portion of the dry pipe and which clamps the yoke formed by the two yoke plates firmly in place when nuts 35 are threaded upon the ends of the bolt and against washers 36 resting upon the 110 upper edge of the yoke. Obviously, by this arrangement, the bracket as a whole may be swung about the dry pipe to bring its standards 16 to vertical position before the nuts 35 are fully turned home and the bracket 115 may be adjusted vertically through the yoke to bring its lower end to any desired level within the boiler. Both brackets are, of course, secured to the dry pipe in this manner and this vertical adjustment of the 120 brackets with respect to the yokes is, therefore, of great importance as in many boilers the dry pipe extends at an angle to the horizontal and as will be later apparent it is essential that the lower ends of all of the 125 yoke standards lie in a common horizontal plane. When the standards are properly adjusted in the yokes, they may be secured against any movement by set bolts 36' threaded through certain of the sleeve por- 130

tions of the yokes and engaging the standards, as shown in Fig. 8 of the drawings.

When the above described supporting frame is in place, a valve fitting 37 is passed inwardly through the boiler and connected to the T-coupling 27, and a pipe 38 is led from this fitting back into the cab of the locomotive to a valve 39 which is to be left open while the engine is being operated. 10 From this valve a nipple 40 connects with a T 41 and a nipple from the side opening of this T leads to a valve 42 from which a discharge pipe 43 leads. This valve 42 is left partially open and blows continuously 15 while there is steam in the boiler. From the other opening of the T 41 a nipple 44 leads to a valve 45 from which a discharge pipe 46 leads. This valve 45, like the valve 39, has a much larger passage than the valve 42 and is to be opened only periodically by 20 the engineer for unusual blowing off of scale, sediment, scum and other impurities from the boiler.

As will be soon explained, each of the 25 inlet frame sections is supported by the standard portions 16 of the brackets lying at the same side of the dry pipe, as is clearly apparent by reference to Fig. 3 of the drawings. These standard sections, while tubular, are not in the form of pipe sections but 30 are cast or otherwise formed to provide adjacent their lower ends a laterally or outwardly directed cylindrical hub 47 having a central passage 48 communicating with the bore of the standard and surrounded at its outer end by an annular chamber 49 formed in the outer face of the hub. Furthermore, each of the standards has a brace arm 50 extending radially from its hub and at a 35 slight downward inclination to receive one end of an arcuate brace and guide bar 51 which is secured to it by a bolt 52 having an unthreaded portion of its shank passed loosely through the end of the guide bar 40 and threaded into the end of the arm 50. The opposite end of the guide bar is fixed 45 to the intermediate portion of the standard section 16 by means of a bolt 53 passed through the end of the guide bar and threaded into a boss reinforcement 54 formed upon 50 the section 16.

The two inlet frame sections of our skimmer are swingingly supported upon the hubs 47 and guide bars 51 and are identical in construction, each including a skimmer pipe 55 having double oscillating joint connection 56 near its ends with tubular connecting arms or pipes 57 which have single oscillating joint connection 58 with the hubs. 60 The double oscillating joints 56 are all alike and a description of one will, therefore, suffice for all. Each of these joints includes a pair of coöperating sleeve members 59 and 60, each in the form of a half sleeve 65 enlarged intermediate its length to provide

a cup shaped body 61, the longitudinal edges of the sleeves and the marginal edges of the cup-shaped bodies being provided with laterally directed clamping flanges 62 perforated to receive rivets 63 by means of which 70 the sleeve sections 59 and 60 may be clamped about the upper end of the correlated pipe section 57 so that the pipe section will communicate at its end with the cylindrical chamber formed by the opposed cup portions 75 61. Caps 64 are seated between the sections of the clamping sleeves more remote from the pipe sections 57 to form in effect closures for the upper ends of such pipe sections. The cup shaped body portions 61 are provided 80 with concentrically formed instruck beads 65 substantially V-shaped in cross section and the cup-shaped body section of the clamping sleeve 60 is also formed with a central opening 66. A pair of corresponding clamping sleeves 67 and 68 are clamped about each end of each skimmer pipe 55 and about the ends of relatively short skimmer pipe sections 55', the cup shaped body of the sleeve 68 being formed with an opening 69, 90 corresponding to the opening 66 of the sleeve 60 and alining therewith. A bush bearing 70 seats in the alined openings 66 and 69 and at one end is formed with an outwardly directed flange 71 engaging 95 against the inner face of the cup shaped body member of the sleeve 60. A second bush bearing 72 projects through the first and has a flange 73 engaging a body member of the clamping sleeve 68 and the free 100 end of this second bush bearing is peened or flared outwardly, as shown at 74, to lock the two bush bearings together and so hold the pair of bearing sleeves 59 and 60 to the bearing sleeves 67 and 68 and still leave 105 them free for turning movement. A ball bearing ring 75 is interposed between the sleeves 60 and 68 and is formed at spaced peripheral intervals with openings to receive balls 76 which seat in the opposed beads 110 of the sleeves 60 and 68 and which thus provide a ball bearing for the joint. Caps 77 fit snugly about the ends of the supplemental skimmer pipe sections 55 and are secured by cap bolts 78. The cap bolts 78 are also preferably employed to secure the pipe sections 55 and 57 and the caps 64 in the various sleeves.

All of the single oscillating joints 58 are identical in construction, being greatly 120 similar to the joints above described. Each of these single oscillating joints includes a pair of clamping sleeves 79 and 80 which are riveted for clamping engagement about the free ends of the pipe sections 57 and 125 about caps 81, corresponding to the caps 64. Each of these joints further includes a securing cup 82, the flange of which fits about the hub 47 of the correlated standard section 16, being secured thereto by cap screws 83, 130

and the body of which is formed with an opening to align with an opening formed in the body of the clamping sleeve 80. Inner and outer bush bearings 84 and 85, corresponding to the bush bearings 70 and 72, secure the clamping sleeves 79 and 80 to the anchoring cup 82 and ball bearings 86 carried in openings in a bearing ring 87 engage in the bead of the body of the bearing sleeve 80 and in a corresponding bead 88 formed in the body of the anchoring cup 82. Cap screws are employed to secure the sleeves 79 and 80 to the pipe sections 57 and counterweights 89 are formed integrally 15 with the outer ends of the caps 81 to counterbalance the swinging intake frame sections, as will be later apparent.

Split sleeves 90 are clamped about the pipe sections 57 and eyes 91, swivelly connected to the sleeves, encircle the guide bars 51 so that the pipe sections 57 and, consequently, the skimmer pipes 55 are held against lateral movement and the various oscillating joints are relieved of any lateral 25 strain. The guide bars 51, adjacent their lower ends, are formed with outwardly directed stop lugs 92 which serve to positively limit downward swinging movement of the pipe sections or arms 57.

Brackets 93 secure a plurality of floats 94 to the skimmer pipes 55 at spaced intervals, as clearly shown in Figs. 2 and 3 of the drawings. Each of these floats includes a pair of cylindrical body members 95 closed 35 at one end and open at the other, said body members adjacent their open ends being outwardly flared to provide an annular shoulder 96 and at their open ends being formed with laterally directed annular flanges 97. A diaphragm 98 is positioned 40 between the flanges of the ends of the body sections 95 and the edge portions of such flanges are bent about themselves to provide a fluid tight locking seam 99 which 45 also serves to hold the diaphragm in place. The diaphragm is formed centrally with a small opening 100 and the resultant float is, of course, fluid tight.

Each bracket 93 includes a body 101 in 50 the form of a split resilient sleeve, the free edges of which are provided with radially extending clamping ears 102 apertured to receive a clamping bolt 103 which, together with a nut 104, serves to clamp the sleeve 55 about the strainer pipe. The ends of the sleeve, at the side opposite the clamping ears, are formed with diverging arms 105 which increase in width toward their free ends and which have their free end edges 60 cut-away, as shown at 106, for engagement against the peripheral face of the float. These edges are formed with inwardly directed fingers 107 and are preferably additionally cut-away centrally, as shown at 108, 65 so that they may be sprung to fit against

pipes of somewhat different sizes. A pair of clamping bands 109, provided at their ends with clamping ears 110, engage about the float and against the shoulders 96 thereof and the fingers 107 seat beneath these 70 bands, as clearly indicated in Figs. 5 and 6. Bolts 111 and nuts 112 serve to clamp the bands in place. Preferably, also cap screws 113 are passed through the body portion 101 of the brackets and threaded into the skimmer pipes to absolutely prohibit any turning 75 of the floats about the pipes.

The skimmer pipes at spaced intervals throughout their length are formed with diametrically opposed inlet slots 114, or 80 other suitable inlet openings, the slots extending longitudinally of the pipes and the slots in each pipe lying in a common horizontal plane, as fully shown in Fig. 2 of the drawings.

The size or buoyancy of the floats is so proportioned with respect to the counterweights 89 and the weight of the swingingly supported inlet frames of the apparatus as to at all times support the skimmer 95 bars so that their slots are at or approximately at the surface of the water in the boiler. As a result, assuming that the valve 39 and one or the other of the valves 42 and 45 are open, the steam pressure in the 95 boiler will force any scum, scale or other impurities coming to the surface of the water through the slots of the skimmer bars, through the skimmer bars to the swinging tubular arms 57, by way of the passages 100 through the double oscillating joints, through the passages of the single oscillating joints in the tubular brackets and from these brackets through the connecting pipe sections to the pipe 38 and so through one 105 or the other of the discharge pipes 43 and 46. Obviously, under normal operating conditions, the smaller valve 42 will be slightly open and the valve 45 closed, the amount to which the valve 42 is opened being governed by the rate of discharge necessary to keep the surface of the water free from impurities with the particular type of water being employed in the boiler. The engineer may, however, from time to time, 115 open the larger valve 45 to permit a rapid blowing off of steam, water and floating impurities from the boiler.

From the foregoing description, it will be apparent that we have provided a boiler skimmer or cleaner which may be readily applied within locomotive boilers of ordinary type and which may be firmly but adjustably secured to the dry pipe of the boiler. The importance of having the supporting brackets 120 secured to the dry pipe in such a manner that they may be initially turned to bring the hub portions of the brackets in a common horizontal plane and in such a manner that they may be vertically adjusted for 125 130

this same purpose will be readily appreciated as it is absolutely essential that the skimmer bars occupy a horizontal position at all times. In installing the cleaner, the 5 standard portions of the brackets should be so adjusted vertically within the yoke that at normal water level in the boiler, the skimmer bar supporting arms 57 will occupy substantially a midway position, as shown in 10 Fig. 2, when the skimmer bars are supported at the surface of the water. Ample range for upward and downward movement of the skimmer bars and their floats, due to changes in water level in the boiler and to surging 15 of water in the boiler, due to movement of the locomotive up and down grades or to its sudden stopping and starting, will therefore be provided for.

It will also be noted that ample provision 20 is made for ready assembly of the parts or ready renewal of any necessary parts in case of injury either through accident or wear. Furthermore, the double and single oscillating joints are of strong construction and operate with remarkable freedom, due to the 25 ball bearings, so that under all circumstances, the skimmer pipes may readily rise and fall with changes in water level.

In some instances, braces, stay bolts and 30 the like are so positioned within the locomotive boiler as to prevent attachment of our improved skimmer or cleaner to the dry pipe. Under these circumstances, special brackets of the type shown in Figs. 11 and 35 12, or of the type shown in Fig. 13, may be employed which are capable of being secured to some of the stay rods or bolts or pipes already in the boiler or of being secured by stay bolts fixed to the shell of the boiler so 40 that the brackets may properly support the skimmer pipes in a common horizontal plane.

The bracket shown in Figs. 11 and 12 is 45 greatly similar to the bracket previously described including the tubular standards 115 having the single oscillating joint receiving hubs 116 and connected by yoke plates 117, corresponding to the yoke plates previously 50 described but relatively short to hold the standards in closely spaced relation. A single tie bolt 118 and nut 119 serve to clamp 55 the standards in adjusted position between the yoke plates and to secure the yoke plates together and cap screws 120 may be passed through the yoke plates and into the standards for additional strength. One of the 60 yoke plates is formed with a laterally directed boss 121 having a vertically formed bore 122 to receive a rod or pipe fixed to the boiler or forming part of the braces therein 65 and a set screw 123 is threaded through this boss for locking engagement with such rod or pipe. The upper ends of the standards of each bracket are connected by a U-shaped coupling member 124 provided with bores 70 125 opening through the ends of its arms and

communicating with a longitudinal bore 126 opening through both sides but closed at its ends by plugs 127. These couplings are provided with lateral branches 128 in order that the couplings may be connected by pipe sections, corresponding to the pipe sections 24, 25 and 26, shown in Fig. 3. A nipple 129 connects the upper end of one standard with one arm of the coupling 124 and a union coupling 130 connects the other standard 75 with the other arm of the coupling 124.

The form of bracket shown in Fig. 13 includes a pair of T-shaped heads 131 of tubular construction provided at the ends of their aligned branches with enlarged hubs 132 80 for receipt of the attaching cups of the single oscillating joints and having their lateral branches connected by the longitudinal pipe 133 which may be in sections connected by suitable couplings and which has a vertically extending discharge pipe 134 which projects through the boiler for connection with the pipe 38. Tie rods 135 have their ends tapped into the hubs at either side of the longitudinal pipe 133 and their adjacent ends adjustably connected by turn buckles 136. Supporting rods or bolts 137 are threaded into the upper faces of the hubs and are secured at their upper ends to the shell of the boiler or other suitable support 95 therein.

Obviously, with either of the above described forms of supporting brackets, the skimmer pipes, together with their floats and counterweighted arms, may be properly supported for easy swinging movement to keep them in a horizontal plane and at the proper level, dependent upon the water level. The operation, of course, is the same, irrespective of the type of bracket employed.

Although we have illustrated and described our improved boiler skimmer or cleaner in all its details of construction, it will of course be understood that we do not limit ourselves to such details, but reserve the 100 right to make any changes, within the scope of the appended claims, without in the slightest degree departing from the spirit of our invention.

Having thus described the invention, what 115 is claimed as new is:—

1. In a boiler skimmer, tubular brackets, tubular connection establishing communication between the brackets, means for supporting the brackets in a boiler, tubular 120 arms having swinging connection at one end with the lower ends of the brackets and disposed in parallel spaced relation, a skimmer pipe having swinging connection with the opposite ends of the arms, the arms having communication both with the pipe and with the brackets and the pipe having inlet openings, closures for the ends of the pipe, floats carried by the pipe, counterweights carried by the opposite ends of the arms 130

whereby the floats and counterweights co-operate to maintain the pipe with its inlet openings at substantially the level of water in the boiler while the arm connections between the pipe and brackets permit vertical movement of the pipe but hold it against angular movement with respect to the brackets, arcuate guide straps carried by the brackets over which the arms move, and sliding connections between the arms and guide straps whereby the arms are braced in their movement.

2. In a boiler skimmer, tubular brackets, tubular connection establishing communication between the brackets, means for supporting the brackets in a boiler, tubular arms having swinging connection at one end with the lower ends of the brackets and disposed in parallel spaced relation, a skimmer pipe having swinging connection with the opposite ends of the arms, the arms having communication both with the pipe and with the brackets and the pipe having inlet openings, closures for the ends of the pipe, floats carried by the pipe, counterweights carried by the opposite ends of the arms whereby the floats and counterweights co-operate to maintain the pipe with its inlet openings at substantially the level of water in the boiler while the arm connections between the pipe and brackets permit vertical movement of the pipe but hold it against angular movement with respect to the brackets, arcuate guide straps carried by the brackets over which the arms move, sliding connections between the arms and guide straps whereby the arms are braced in their movement, and stops carried by the guide straps to limit downward swinging of the arms and consequent downward movement of the pipe.

3. In a boiler skimmer, a yoke adapted to be clamped to the dry pipe of a boiler, a supporting bracket clamped in the yoke and vertically adjustable therein, a skimmer element having swinging connection with the bracket and provided with an inlet opening, the skimmer element, connection and bracket being formed with a communicating passage, means for discharging material from the passage, and floats for supporting the skimmer element with its opening at substantially the water level in the boiler.

4. In a boiler skimmer, a tubular frame, all parts of which are in communication with each other, a discharge pipe leading from the frame, oscillating joint connections between certain parts of the frame whereby certain frame elements are supported for vertical movement, floats carried by such elements, the float carrying ele-

ments being formed with inlet openings and their parts held at substantially the water level of the boiler by the floats, and means for adjustably securing the frame within a boiler, said means including yokes adapted to be clamped to the dry pipe of the boiler and to adjustably clamp certain elements of the frame.

5. The combination with a locomotive boiler, and its dry pipe, of a pair of substantially U-shaped tubular brackets straddling the pipe with their sides projecting downwardly, means adjustably clamping the brackets to the pipe, elongated tubular skimmer elements, floats for supporting the elements, and tubular connecting means between the elements and brackets whereby the elements have vertical movement but will always lie in one or another of a series of parallel planes.

6. The combination with a locomotive boiler, and its dry pipe, of a pair of substantially U-shaped tubular brackets straddling the pipe with their sides projecting downwardly, means adjustably clamping the brackets to the pipe, elongated tubular skimmer elements, floats for supporting the elements, tubular connecting means between the elements and brackets whereby the elements have vertical movement but will always lie in one or another of a series of parallel planes, and means for discharging matter from the brackets.

7. The combination with a locomotive boiler, and its dry pipe, of a pair of substantially U-shaped tubular brackets straddling the pipe with their sides projecting downwardly, means adjustably clamping the brackets to the pipe, elongated tubular skimmer elements, floats for supporting the elements, tubular connecting means between the elements and brackets whereby the elements have vertical movement but will always lie in one or another of a series of parallel planes, and means for discharging matter from the brackets, said means including a tubular connection between the brackets and a valved discharge pipe leading from such connection.

8. The combination with a locomotive boiler and its dry pipe, of yokes clamped to the dry pipe and providing clamping sleeves, brackets clamped in the sleeves, and skimmers swingingly supported by the brackets.

In testimony whereof we affix our signatures.

EUGENE N. PHILLIPS. [L. S.]
HARVEY H. DICK. [L. S.]
